UNITED STATES PATENT OFFICE

VINCENT P. DOLE, OF CHICAGO, ILLINOIS, ASSIGNOR TO OLD MONK OLIVE OIL CO., OF CHICAGO, ILLINOIS, A CORPORATION OF ILLINOIS

DESIGN FOR A BOTTLE

Application filed October 7, 1931. Serial No. 41,329. Term of patent 14 years.

To all whom it may concern:

Be it known that I, VINCENT P. DOLE, a citizen of the United States, residing at Chicago, in the county of Cook, State of Illinois, have invented a new, original, and ornamental Design for Bottles, of which the following is a specification, reference being had to the accompanying drawing, forming a part hereof, wherein the single figure of the drawing represents in elevation a bottle showing my new design. It will be understood that the bottle is of circular outline in

horizontal cross-section, as indicated by the shading, and that the broad corrugations above the truncated, approximately hemispherical base decrease successively in size, so that the general outline is that of a broad bottomed bottle tapering in regular approximately spherical sections from the base to the neck portion.

I claim:

The ornamental design for a bottle, substantially as shown and described.

VINCENT P. DOLE.
